BEIRNE GORDON, JR., AND ROBERT McCARTY, OF UTICA, NEW YORK, ASSIGNEES TO THE SKENANDOA COTTON COMPANY, OF UTICA, NEW YORK, A CORPORATION OF NEW YORK.

WINDING AND DYEING MECHANISM.

Application filed December 4, 1923. Serial No. 678,403.

To all whom it may concern:

Be it known that BEIRNE GORDON, Jr., and ROBERT McCARTY, citizens of the United States, and residents of Utica, in the county

5 of Oneida and State of New York, have invented certain new and useful Improvements in Winding and Dyeing Mechanism, of which the following is a specification.

This invention relates to the dyeing of 10 yarn in the process of winding and more particularly to the application of the color or dye to the yarn intermittently or periodically so as to produce yarn having alternate lengths colored and uncolored which is required for producing certain desired effects 15 in the fabric, to be knitted or otherwise produced therefrom, and consists in an improved and simplified device better adapted for more successfully producing the alternate or "random" dyeing of the yarn than has been heretofore accomplished.

Our improved mechanism for the alternate application of dye to yarn is designed particularly to be incorporated with and as 20 an attachment to the type of winding machine employing a traverse or reciprocating type of thread guide operating in conjunction with the winding spindle, as for instance the winding machine known commercially as the Foster winder. An important 25 feature of our improved device, as associated with the traverse type of winding machine, consists in the employment of the traverse or reciprocating movement of the 30 yarn as the instrumentality for making and breaking contact of the yarn with the color applying means for applying the color alternately to spaced lengths of the yarn as desired. The improved arrangement accordingly 35 effects a substantial economy of parts by the elimination of special mechanism to make and break engagement with the dye applying surfaces and moreover as associated with the specific type of winding machine referred to possesses the further and 40 valuable advantage of insuring uniform results as to the length of and spaced relation of the dyed portions irrespective of the speed of the winding operation and rate of 45 the movement of the yarn through the machine.

Other important features and advantages of our improved mechanism will be understood by reference to the accompanying

drawings wherein like reference characters 55 of the accompanying description are applied to the corresponding parts in the several views.

In the drawings our improved mechanism is illustrated diagrammatically of which, 60 Fig. 1 is a plan view of an approved in-

stallation.

Fig. 2 is a view in front elevation.

Fig. 3 is a view in vertical cross-section and 65

Fig. 4 is a view corresponding to the latter and illustrating a suitable modified device for producing the alternate dyeing effect.

In the preferred embodiment of the features of our invention as illustrated in Fig- 70 ures 1, 2 and 3 the improved mechanism for applying the dye to the yarn in alternate lengths is shown incorporated with and operatively associated with a traverse acting winding machine of the type referred to 75 wherein the yarn *a* is passed upwardly from a supply-cop or bobbin 1 with a continuous feed movement through stationary guide 2 and traverse guide 3 to the winding spindle where the yarn is wound upon conical tubes or shells 4 to produce a conical spool as here illustrated, suitable for use as supply spools in knitting machines. In the standard type of traverse action winding machine, as here illustrated diagrammatically, the winding mechanisms are assembled and operated in multiple with the traverse or reciprocating thread guides 3 80 mounted upon a traverse bar 5 operating with a reciprocating movement longitudinally of the bar and the tubes 4, or wound spools 4' are rotated by having bearing and driving engagement with continuously driven driving drum 6 mounted upon the longitudinally extended driving shaft 7. 85

In accordance with our present invention, the means applying the color or dye to the 90 yarn is positioned or interposed between the stationary yarn guide 2 and the traverse or reciprocating guide 3 in suitable manner whereby the lateral motion imparted to the 95 yarn will be operative to bring the yarn in and out of contact with a dye applying element. As here shown the means for applying the dye to the yarn consists of a color 100 roller 9 which is a cylindrical roller mounted upon the longitudinal extending roller shaft 10; it being understood that a color 105

roller is provided for each of the winding spindles in the multiple construction customarily employed. The color roller 9 is positioned within a longitudinally extending trough or tank 11 for the dye liquor which is arranged at a level to submerge the lower portion of the roller and the dye roller 9 is progressively rotated by the rotation of the shaft 10 through suitable driving connections with either a continuous or intermittent motion as may be desired. As a result the surface of the roll 9 is constantly supplied with dye liquor and the position and diameter of the dye roll is such that its upper peripheral surface is in the normal path of the yarn passing from the guides 2 to traverse guide 3 whereby the yarn when positioned thereover will have wiping contact with the roller surface to receive the dye therefrom. The dye roll 9 is here shown positioned in alignment with the central transverse plane of the winding spindle and is of relatively shortened length whereby the action of the traverse movement will move the yarn into and out of engagement with the color transferring or outer peripheral surface of the roll. The length of the color applying surface of the color roll 9, as here shown, corresponds approximately to one-half the distance of the traverse movement of the yarn on the line of engagement with the roll with the result that the yarn will be dyed in alternating lengths with intervening undyed lengths or spacing corresponding to the length of the dyed portions. The arrangement as described thus provides for alternate or random dyeing by the movement into and out of contact with a dye roll of the yarn during its normal traverse movement as related to the winding operation. In addition to thereby eliminating the requirement of special means for moving the yarn into and out of contact with the dye roll this arrangement offers the further advantage that the wiping contact of the yarn with the surface of the roll is a component of a forward motion related to the progressive feed of the yarn and a lateral motion transmitted by the traverse guide resulting in a more efficient and uniform transferring of the dye to the yarn in that the yarn is constantly engaging a renewed surface of the roller. As illustrated the dye rollers 9 are desirably formed with beveled or otherwise inclined surfaces 12 to facilitate the passage of the yarn onto the acting surface of the roll.

As will be readily appreciated, the length of the dye applying rolls may be varied with relation to the traverse movement of the yarn to produce variations in the length of yarn to which the color is applied. This obviously may be accomplished by employing dyeing rolls of varying lengths or by varying the position of the guide roll with

respect to the path of movement of the yarn. In the operation of the winding mechanism of the type described it will be understood that the movement of the traverse guide 3 maintains a constant ratio with respect to the feed movement of the yarn and accordingly the application of color to the yarn in the described arrangement will be uniform irrespective of the speed at which the machine is run.

In Figure 4 we have illustrated diagrammatically a further and modified type of our mechanism adapted for intermittently applying color to yarn during the winding process wherein 12' indicates a supply cop or bobbin from which the yarn α' passes upwardly through a stationary guide 13, through a traverse guide 14, to the wound spool 15 having bearing and driving support upon the driving drum. For applying the color in alternating lengths a segmental color roll 17 is suitably journaled to operate within a color trough or vat 18, the color roll in this instance being of a length to contact with the yarn throughout the full traverse movement. The roller 17 is suitably rotated to effect the transfer of the color to the yarn when the segments are in position to engage the yarn and to leave portions of the yarn uncolored when the segments are in intermediate position and accordingly out of contact with the yarn. This arrangement accordingly provides a mechanism suitable for the intermittent application of the color to the yarn with the advantage that in the transfer of the color to the yarn the yarn will be moved both forwardly and transversely over the periphery of the roll so as to obtain an adequate and uniform supply of dye material therefrom.

While we have illustrated and described an approved embodiment of the features of our invention it will be understood that many variations may be made therein without departing from the scope of the invention as defined in the appended claims. It is accordingly intended that all matter herein shall be interpreted as illustrative and not in a limiting sense. As illustrative thereof it will be understood that while there is here shown a single and relatively shortened dye roller for each of the spindles, it is apparent that two or more shortened and spaced dye rollers may be employed and positioned within the plane of movement of the yarn in its traverse movement so as to produce different color effects.

Having described our invention we claim:

1. In a mechanism of the character described, the combination with a winding machine comprising means to transfer yarn or the like from one holder therefor to another and having a traverse or reciprocating guide operative to impart a traverse

- movement to the yarn, of means to apply coloring matter to the yarn, intermittently, said means being positioned within a portion of the plane of the traverse movement of the yarn whereby the coloring matter is transferred thereto by engagement of the yarn with the color applying means during a portion of its traverse movement only, substantially as described.
- 10 2. In a mechanism of the character described the combination with a winding machine comprising means to transfer yarn or the like from one holder therefor to another and having a traverse or reciprocating guide operative to impart a traverse guiding movement to the yarn, of means to apply coloring matter to the yarn consisting of a dye roller rotated within a dye bath, said roller having its upper color transferring surface interposed between the stationary and traverse guides and positioned within the plane of the traverse movement of the yarn and being of a length fractional of the length of the traverse movement of the yarn in the plane of contact therewith whereby the traverse movement of the yarn will alternately effect engagement and disengagement of the yarn with the color roller and the coloring matter will be transferred by a wiping contact of the yarn with the color roller as a component of a forward motion resulting from the feed movement of the yarn and a lateral motion transmitted thereto by the traverse guide, substantially as described.
- 15 3. In a mechanism of the character described the combination with a winding machine comprising means to transfer yarn or the like from one holder therefor to another and having a traverse or reciprocating guide operative to impart a traverse guiding movement to the yarn, of means to apply coloring matter to the yarn intermittently, said means consisting of a color roller rotatable within a dye bath and having its upper color transferring surface positioned within the plane of the traverse movement of the yarn and having its said transferring surface of a length less than the transverse movement of the yarn in the line of contact therewith whereby the traverse movement will effect the alternate engagement and disengagement of the yarn with the roller for the coloring of the yarn in alternate lengths.
- 20 4. In a mechanism of the character described, the combination with a winding machine comprising means to transfer yarn or the like from one holder therefor to another and having a stationary guide and a traverse or reciprocating guide operative to impart a traverse guiding movement to the yarn, of means to apply coloring matter to the yarn consisting of a dye roller rotated within a dye bath, said roller having its upper color transferring surface interposed between the stationary and traverse guides and positioned within the plane of the traverse movement of the yarn and being of a length fractional of the length of the traverse movement of the yarn in the plane of contact therewith whereby the traverse movement of the yarn will alternately effect engagement and disengagement of the yarn with the color roller and the coloring matter will be transferred by a wiping contact of the yarn with the color roller as a component of a forward motion resulting from the feed movement of the yarn and a lateral motion transmitted thereto by the traverse guide, substantially as described.
- 25 5. In a mechanism of the character described, the combination with a winding machine comprising means to transfer yarn or the like from one holder therefor to another and having a stationary guide and a traverse or reciprocating guide operative to impart a traverse guiding movement to the yarn, of means to apply coloring matter to the yarn consisting of a dye roller rotated within a dye bath, said roller having its upper color transferring surface interposed between the stationary and traverse guides and positioned within the plane of the traverse movement of the yarn and being of a length fractional of the length of the traverse movement of the yarn in the plane of contact therewith whereby the traverse movement of the yarn will alternately effect engagement and disengagement of the yarn with the color roller and the coloring matter will be transferred by a wiping contact of the yarn with the color roller as a component of a forward motion resulting from the feed movement of the yarn and a lateral motion transmitted thereto by the traverse guide, substantially as described.
- 30 6. In a mechanism of the character described, the combination with a winding machine comprising means to transfer yarn or the like from one holder therefor to another and having a stationary guide and a traverse or reciprocating guide operative to impart a traverse guiding movement to the yarn, of means to apply coloring matter to the yarn consisting of a dye roller rotated within a dye bath, said roller having its upper color transferring surface interposed between the stationary and traverse guides and positioned within the plane of the traverse movement of the yarn and being of a length fractional of the length of the traverse movement of the yarn in the plane of contact therewith whereby the traverse movement of the yarn will alternately effect engagement and disengagement of the yarn with the color roller and the coloring matter will be transferred by a wiping contact of the yarn with the color roller as a component of a forward motion resulting from the feed movement of the yarn and a lateral motion transmitted thereto by the traverse guide, substantially as described.

Signed at Utica, in the county of Oneida and State of New York, this 27th day of November, A. D. 1923.

BEIRNE GORDON, JR.
ROBT. McCARTY.
